UNITED STATES PATENT OFFICE.

GEORGE O. DRAPER, OF HOPEDALE, MASSACHUSETTS, ASSIGNOR TO THE DRAPER COMPANY, OF SAME PLACE AND PORTLAND, MAINE.

SPINDLE AND BEARING.

SPECIFICATION forming part of Letters Patent No. 609,760, dated August 23, 1898.

Application filed December 1, 1897. Serial No. 660,371. (No model.)

To all whom it may concern:

Be it known that I, GEORGE O. DRAPER, of Hopedale, county of Worcester, State of Massachusetts, have invented an Improvement 5 in Spindles and Bearings, of which the following description, in connection with the accompanying drawings, is a specification, like letters on the drawings representing like parts.

This invention has for its object the production of novel means for supporting and adjusting the bolster of a spinning-spindle in the bolster-case in such manner that the proper fit between the tapering pintle of the spindle 5 and the bolster may be readily and quickly effected.

Figure 1 is a vertical sectional view of a spindle-bearing embodying one form of my invention. Fig. 2 is a detail, partly in elevation and section, of the bolster and spindle-pintle, the bolster-support, and a portion of the bolster-case shown in Fig. 1. Fig. 3 is a perspective detail of the bolster-support shown in Figs. 1 and 2.

The spindle S, having a tapering pintle, the bolster-case B, having a threaded shank B' extended through the rail C, the nut B² to retain the case in position, the sleeve-whirl W, secured to the spindle, and the bolster 5 D may be and are substantially of usual or well-known construction.

In the drawings the bolster-support is shown as a compressible ring f, split at f' and held in position in the bolster-case by frictional pressure against the walls thereof in vertically-adjusted position. The lower end of the bolster D rests upon this support, while the lower end of the pintle of the spindle extends freely through said support and rests 5 on the step or end bearing D^X. I have provided the lower end of the bolster with a lug d, which enters the slot f' of the bolster-support, and thereby the bolster is held from rotation, rotation of the support being prevented 5 by its frictional engagement with the bolster-

case. The support is inserted in the case, and it is pushed down by the bolster until the end of the spindle rests on the step and the vertical adjustment of the bolster is effected.

In the construction herein described it will be obvious that the bolster is sustained by or on a support having frictional engagement with and adapted to be moved vertically in the bolster-case to thereby effect the vertical 55 adjustment of the bolster relative to the pintle of the spindle.

Having fully described my invention, what I claim, and desire to secure by Letters Patent, is—

1. The combination with a bolster-case, of a bolster, an expansible annular support for and located entirely below the bolster, and means to positively hold the bolster from rotation, said support being held in vertical adjustment at any point in the bolster-case 65 solely by frictional engagement therewith.

2. A bolster-case, a bolster having a lug at its lower end, a split ring vertically movable in and held frictionally by the bolster-case, 70 the lower end of the bolster resting on said ring with the lug projecting between the ends of the ring.

3. A bolster-case, a bolster loosely held therein, and a split ring engaging the inner 75 wall of the bolster-case at any point thereof and being held in adjusted position thereat by its frictional contact, the lower end of the bolster resting on the ring, one of said parts having a projection and the other part a notch 80 to receive the projection, to prevent rotation of the bolster.

In testimony whereof I have signed my name to this specification in the presence of two subscribing witnesses.

GEORGE O. DRAPER.
